UNITED STATES PATENT OFFICE.

LOYD R. STOWE, OF ST. LOUIS, MISSOURI.

FURNACE LINING.

Application filed September 4, 1926. Serial No. 133,671.

This invention relates to refractory linings for furnaces and has for its principal objects to provide a brickwork furnace lining which can be readily attached to the metal framework of the furnace and which will automatically accommodate itself to temperature changes without injury to the lining and without affecting its heat insulating qualities. Other objects are to produce a furnace lining constructed of fire bricks of such size that they can be placed in brickwork with other standard firebrick shapes without any alteration or special handling. Another object is to secure an offsetting or staggering of the joints between the bricks in one course with relation to the joints between the bricks in the contiguous courses. Other objects are to permit the removal and replacement of bricks located between adjacent framing members of the furnace without disturbing any other bricks.

The invention consists in the improved fire bricks and in the manner of attaching such bricks to the framework of the furnace to form a brick lining therefor. It also consists in the parts and in the arrangements and combinations of parts hereinafter described and claimed.

In the accompanying drawing, which forms part of this specification and wherein like symbols refer to like parts wherever they occur.

Figures 1 and 2 are vertical transverse sections through the metal framework of the crown or ceiling of a furnace equipped with a lining embodying my invention, the sections being taken longitudinally of adjacent courses of brick on the lines 1—1 and 2—2, respectively, in Figure 3;

Figure 3 is a view looking at the under side of the lining shown in Figures 1 and 2; and

Figure 4 is a horizontal cross section through the side framing members of the furnace showing a lining embodying my invention attached thereto.

Referring to the accompanying drawing, my invention is shown in connection with the metal framework at the top or sides of a furnace. As shown in drawing, said framework comprises spaced parallel framing members preferably in the form of bulb

beams 5 disposed with their webs vertical. This construction of furnace framework is well known and it is considered unnecessary to illustrate it in detail. 55

Attached to the bulb beams 5 of the framework of the furnace is a lining 6 comprising two sets of refractory bricks "A" and "B", the bricks being of substantially the same weight and size as a standard firebrick. The bricks of the kind "A" are provided at one side adjacent to one corner with a relatively shallow V-shaped groove or notch 7; and the bricks of the kind "B" are provided at one side adjacent to one corner with a relatively deep V-shaped groove or notch 8. 60

As shown in the drawing, the bricks are laid in courses, each course extending transversely of the bulb-shaped framing members 5 at the top or sides of the furnace and comprising bricks of the kind "A" alternating with bricks of the kind "B". Said bricks are arranged with their length transverse to the framing members 5 of the metal framework of the furnace and with their body portions extending inwardly beyond the lateral side flanges of said framing members to from the refractory brickwork lining 6 therefor. 70

Each course or row of brick has two bricks, one brick of the kind "A" and one brick of the kind "B" disposed between adjacent framing members; and said bricks are arranged with the shallow notch of the brick "A" in engagement with the adjacent flange of one framing member and with the deep notch of the brick "B" in engagement with the adjacent flange of the other framing member. With this arrangement of the notched bricks "A" and "B," the main body portion of the bricks overlap or cover the bulb flanges of the framing members, and the different depths of the notches therein bring about an offsetting of the joints in adjacent courses along the center lines of the bulb beams and lines passing midway therebetween. The advantage of this staggering or breaking of the joints in adjacent courses on opposite sides of the center lines of the framing members, is that it tends to prevent cracking of the lining along said members and thus expose them to the action of fire. 80

100

As shown in Figures 1 and 2 of the drawing, the bricks, when suspended from the lower flanges of the bulb beams at the top of the furnace, tend to pivot or rock on the supporting flanges of said beams and thus bring the corners of the bricks into abutting relation at diagonally opposite corners, thereby forming V-shaped joints between adjacent bricks. As shown in the drawing the joints at the bulb beams are narrowest at the inner ends of the bricks and gradually widen towards the notches; and the joints located between the bulb members are narrowest at the outer ends of the bricks and gradually increase in width at the inner ends thereof. By the arrangement just described the bricks are suspended from the bulb beams adjacent to one corner with every brick in a row touching the bricks adjacent thereto at diagonally opposite corners with the result that the brickwork lining structure acts after the manner of an accordion, being continuously sealed against air and, at the same time, permitting each individual brick to expand or contract and thus accommodate itself automatically to temperature changes. As shown in the drawing, the corners of the bricks are preferably coped off or beveled, as at 10, adjacent to their notched portions so as to provide a proper clearance between said corners and the ends of the supporting beams during the pivoting or rocking of the bricks on the supporting flanges of said beams.

Obviously, the hereinbefore described construction admits of considerable modification without departing from the invention, and I do not wish to be limited to the precise construction shown.

What I claim is:

1. A furnace lining comprising spaced parallel frame members, bricks of substantially standard fire-brick dimensions arranged in courses extending transversely of said frame members, said bricks being arranged in pairs between adjoining frame members and having notched sides adapted to engage said frame members, the bricks of each pair having notches of different depths, and the bricks being so engaged with the frame members that the shallower-notched bricks alternate with the deeper-notched bricks in directions longitudinal and transverse of the frame members.
2. A furnace lining comprising spaced parallel frame members, bricks of substantially the same cross-sectional size and shape arranged in courses extending transversely of said members, said bricks being arranged in pairs between adjoining frame members and the bricks of each pair having notches in one side thereof adapted to engage said frame members, the notches in the bricks of each pair being of different depths, and the bricks being so engaged with said frame

members that the joints in one course are offset or staggered with relation to those in the contiguous courses.

3. A furnace lining comprising spaced parallel frame members having flanges at each side thereof, bricks arranged in courses extending transversely of said frame members, said bricks being arranged in pairs with the inner ends of a pair disposed between adjoining frame members and provided with notches adapted to engage the flanges of said frame members, the bricks of each pair having notches of different depths, and the bricks being so engaged with the flanges of said frame members that the joints between the bricks in one course are offset with relation to the joints between the bricks in the courses adjacent thereto.

4. A furnace lining comprising spaced parallel supporting members provided with lateral flanges, bricks disposed in courses extending transversely of said supporting members with their end portions extending therebetween, the portions of the bricks located between said supporting members being provided with notches adapted to engage the flanges thereof, and the portions of the bricks located beyond said framing members being of the same cross-sectional size and shape, the notches in some of the bricks being relatively deep, and the notches in the other of said bricks being relatively shallow, the bricks being so mounted on the supporting members that the bricks having the shallow notches alternate with those having the deep notches both longitudinally and transversely of the supporting members, whereby the joints between the bricks in one course are offset with relation to the joints between the bricks in the courses adjacent thereto.

5. A building unit for brickwork, said unit comprising two bricks of substantially the same dimensions, each of said bricks having a groove in one side, the groove in one of said bricks being of greater depth than the groove in the other of said bricks, as and for the purpose described.

6. A furnace lining comprising spaced parallel frame members, bricks arranged in courses extending transversely of said members, said bricks being arranged in pairs between adjoining frame members, and having notched sides adapted to engage said frame members, the bricks of each pair having notches of different depths, and the bricks being so mounted on the frame members that the spaces between the bricks in one course are offset with relation to those in the contiguous courses and the space at one side of a brick in a course tapers in one direction and the space at the opposite side of said brick tapers in a reverse direction.

7. A furnace lining comprising parallel

spaced horizontal framing members provided with lateral flanges, bricks disposed in courses extending transversely of said members with their upper ends disposed 5 therebetween, each of said bricks being provided adjacent to one of its upper corners with a notch adapted to engage the lateral

flange of a framing member, each brick in each course abutting adjacent bricks in such course at its diagonally opposite corners. 10

Signed at St. Louis, Missouri, this 30th day of August, 1926.

LOYD R. STOWE.
